(57) **CLAIM**

I claim the ornamental design for a curvaceous carton, as shown and described.

DESCRIPTION

FIG. 1 is a front perspective view of a first embodiment of the curvaceous carton of our new design.

FIG. 2 is a right side elevational view thereof.

FIG. 3 is a left side elevational view thereof.

FIG. 4 is a rear elevational view thereof.

FIG. 5 is a front elevational view thereof.

FIG. 6 is a front perspective view of a second embodiment of the curvaceous carton, similar to FIG. 1 except for the rear panel which includes vertical edges that are substantially linear instead of curvilinear.

FIG. 7 is a right side elevational view of the second embodiment shown in FIG. 6.

FIG. 8 is a left side elevational view of the second embodiment shown in FIG. 6; and,

FIG. 9 is a rear elevational view of the second embodiment shown in FIG. 6.

The top and the bottom are flat and devoid of surface ornamentation.
